United States Patent Office

Des. 231,863

Patented June 18, 1974

231,863

SPIRIT DUPLICATOR OR SIMILAR ARTICLE

David E. Anderson, Highland Park, Ill., assignor to
Bell & Howell Company, Chicago, Ill.

Filed May 19, 1972, Ser. No. 255,304

Term of patent 14 years

Int. Cl. D18—02

U.S. Cl. D64—11 B

Fig. 1.

Fig. 2.

FIG. 1 is an isometric view of a spirit duplicator or similar article showing my new design, the unseen side being substantially identical to the side shown except for the omission of the control knob and rectangular panel therefor; and

FIG. 2 is a rear elevational view of the design shown in FIG. 1.

I claim:

The ornamental design for a spirit duplicator or similar article, as shown and described.
